UNITED STATES PATENT OFFICE

BRONSON C. WOODFORD, JOSEPH BEHLE, AND JOSHUA C. CONRAD, OF DALLAS, TEXAS,
ASSIGNORS TO THE MURRAY COMPANY, OF DALLAS, TEXAS, A CORPORATION OF
TEXAS

BELT DISTRIBUTOR FOR COTTON GINS

Application filed January 10, 1929. Serial No. 331,620.

This invention relates to new and useful improvements in belt distributors for cotton gins.

One object of the invention is to provide a belt distributor in which the belt driving, carrying and tensioning elements are made in individual units, whereby easy, convenient and expeditious assembly of the distributor may be carried out.

10 A particular object of the invention is to provide a belt distributor which, owing to its novel features, may be constructed of metal, thus reducing fire hazards in the ginning system.

15 A further object of the invention is to provide an improved take-up unit for tensioning the belt, arranged to be easily adjusted under a load.

Another object of the invention is to provide 20 a doffing and discharge mechanism for disposing of cotton which finds its way under the belt and accumulates on the pulley.

Still another object of the invention is to provide an idler and transmission unit arranged to readily slide, thus reducing friction and making for quick assembly.

Another object of the invention is to provide 30 a driving unit including a compact and simple drive and equipped with a choke valve arranged to automatically open and accommodate the cotton in case of a congestion in the distributor.

A construction designed to carry out the 35 invention will be hereinafter described, together with other features of the invention.

The invention will be more readily understood from a reading of the following specification and by reference to the accompanying 40 drawings, in which an example of the invention is shown, and wherein:

Fig. 1 is a fragmentary side elevation of a belt distributor assembly constructed in accordance with the invention.

45 Fig. 2 is an enlarged longitudinal vertical sectional view of the discharge end of the distributor,

Fig. 3 is a longitudinal horizontal sectional view of the driving unit,

50 Fig. 4 is a side elevation of the same,

Fig. 5 is a side elevation of the idler section,

Fig. 6 is a longitudinal horizontal sectional view of the same,

Fig. 7 is an end elevation of said section,

Fig. 8 is a side elevation of the take-up unit,

Fig. 9 is a plan view of the same, and

Fig. 10 is an isometrical view of the driven end.

In the drawings the numeral 10 designates an elongated distributor housing which is preferably constructed of sheet metal and suitably reenforced by angles 11. The housing is conveniently built of sections and includes a driving end section A, a discharge section B and a central or idler section C. These sections are constructed with the angles 11 at one or both ends so as to be conveniently secured to the other sections of the housing. As is shown in the drawings, the intermediate or longitudinal central portion of the housing may be open.

The section A is provided with a bonnet 12 in which a pulley 13 is mounted upon a drive shaft 14 so as to be rotated by said shaft, as is best shown in Figs. 3 and 4. The shaft is journaled in anti-friction bearings 15 suitably mounted on each side of said bonnet. A beveled gear 16 fastened on one end of the drive shaft is driven by a beveled pinion 17 made fast upon a countershaft 18. The countershaft is journaled in anti-friction bearings 19, one of which is supported in a bracket 20 on the side of the bonnet and the other of which is supported in a bracket 21 on the side of the section A. The countershaft may be suitably driven from any power source.

The section B has a discharge hood 22 over its open end. A belt take-up device (Figs. 8 and 9) is mounted on the section B and includes longitudinal side channels 23 connected by a crosshead 24 at one end and carrying anti-friction bearings 25 at their opposite ends in which a driven shaft 26 is journaled. A pulley 27 is fastened on the shaft within the housing section.

An adjusting screw 28 is rotatably confined in the crosshead 24 and has screw-threaded 100

engagement in a boss 29 formed in a crossbar 30 suitably fastened to the inner end of the section B and transversely thereof. A hand wheel 31 is fastened on the outer end of the screw, whereby the latter may be rotated to cause longitudinal movement of the members 23. The side channels 23 are supported by flanged guide rollers 32 mounted on the sides of the section B.

10 The distributor may be erected without the idler section C and in such cases the end sections A and B are suitably connected to the intermediate housing sections. The pulleys 13 and 27 have their faces formed with circumferential grooves 33 suitably spaced to receive the heads of the pins 34 of the distributor belt 35, as is best indicated in Fig. 7. This permits the belt to lie flat on the face of the pulleys and at the same time allows the pins to be properly headed. It is obvious that the belt may be properly tensioned by adjusting the screw 28, whereby the pulley 27 is moved longitudinally and the slack taken out of the belt.

15 20 On each side the section B is partially enclosed by a side plate 36, as is particularly shown in Figs. 2 and 10. These plates are provided with longitudinal slots 37 through which the shaft 26 extends. Cover plates 38 carried by said shaft are long enough to cover the slots, irrespective of the adjustment of said shaft. This arrangement prevents cotton, dirt and trash either passing into the section or out of it in the vicinity of the shaft, 25 and thus protects the pulley as well as component parts. The belt 35 travels in the direction of the arrow in Fig. 2 and the hood 22 has a tendency to catch cotton thrown from the belt, as it rounds the pulley 27, and deflect such cotton onto the floor of the gin house. Only such cotton as passes the gin chutes will be so deflected.

25 The upper run of the belt travels on a board or supporting plate 39 suitably fastened in the housing above the longitudinal opening. Considerable difficulty is experienced with cotton lodging between the pulley 27 and the underside of the belt. This results from the fact that the drive pulley 13 not being adjustable, the board 39 may be extended to said pulley, just so there is clearance therebetween, but at the other end the board must be terminated short of the pulley 27 so as to permit adjustment of the latter.

30 35 In order to remove the cotton which finds its way around the edges of the belt and accumulates on the pulley 27, a slide plate 40 is mounted upon the board 39 and supports the belt. This slide has a downwardly directed transverse doffer 41 at its end contiguous to the face of the pulley 27. The slide is fastened to a transverse brace 42 (Figs. 2 and 8) adjacent the doffer and this brace is carried by a transverse angle bar 43 extending through the slots 37 and secured in

the cover plates 38. By this arrangement the doffer is adjusted in unison with the pulley. The cotton which is doffed from the pulley is carried by the belt over the slide 40 and board 39 to a discharge spout 44 (Fig. 8), which delivers it to the huller breast of the gin below.

35 40 As is well understood the cotton is fed to the top leg of the belt and travels toward the bonnet 12. It sometimes happens that an over-supply of cotton is fed to the belt and chokes up in the bonnet 12 and in section A. To care for this condition, an elongated choke valve 45 is hinged to the section A (Fig. 4) at its point of connection with the bonnet so as to open upwardly toward the flow of cotton. The cotton must pass under this valve which rests upon the top of the housing. An over-supply of cotton will raise this valve, as is shown in dotted lines in Fig. 4, thus preventing choking in the bonnet.

45 50 Where the belt distributor must be of considerable length, the idler section C is employed, and in such an instance two belts 351 and 352 are employed, said belts being in all respects the same as the belt 35. The idler section C is best shown in Figs. 1, 5, 6 and 7. This section includes a carriage comprising longitudinal side channels 46 mounted on flanged guide rollers 47 journaled on the sides of the section. The section C has longitudinal side openings 48.

55 60 The belts are mounted on pulleys 13' and 27' of substantially the same structure as the pulleys 13 and 27. The pulleys 13' and 27' are made fast upon shafts 49 which extend through the openings 48 and are journaled in anti-friction bearings 50 carried by the channels 46. Sprocket wheels 51 fastened on the outer ends of said shafts are 65 connected by a chain 52 so that the belt 351 being driven by the pulley 13 drives a pulley 13' which in turn drives the pulley 27' through the agency of the chain 52.

65 70 In order to prevent cotton escaping from between the idlers, as well as for keeping out trash, guard plates 53 extending between the shafts 49 bear against the inner faces of the side walls of the section C and are fastened to guide blocks 54 slidably in the opening 48. When the take-up is operated to adjust the pulley 27 the carriage, which includes the channels 46, will also be adjusted longitudinally to take up the slack in both belts.

75 80 Various changes in the size and shape of the different parts, as well as modifications and alterations, may be made within the scope of the appended claims.

85 90 What we claim is:

95 100 1. In a belt distributor, an elongated metal housing comprising end sections and intermediate sections having an idler section therebetween, all of said sections being individual units secured end to end, pulleys mounted in the end and idler sections, dis-

tributor belts upon said pulleys, a take-up for adjusting the pulley in one of the end sections, and a carriage longitudinally movable on the idler section and on which the 5 idler pulleys are mounted.

2. In a belt distributor, an elongated metal housing comprising end sections and intermediate sections having an idler section therebetween, all of said sections being individual units secured end to end, pulleys mounted in the end and idler sections, distributor belts upon said pulleys, a take-up for adjusting the pulley in one of the end sections, a carriage longitudinally movable 10 on the idler section and on which the idler pulleys are mounted, means for doffing cotton from the pulley carried by and movable with the take-up and a supporting plate co-operating with the belt and doffer for conducting the doffed cotton to a discharge. 15

3. In a belt distributor, a housing having an end section provided with side slots, cover plates over the slots of said section, a shaft passing through said plates, a pulley 20 mounted on the shaft within the section, a belt take-up mounted on the section and connected with said shaft, and a cotton doffer mounted upon the cover plates and disposed in said section contiguous to said pulley and 25 movable therewith and having means to feed doffed cotton beneath the belt.

4. In a belt distributor, an end housing section provided with side slots, a take-up carriage longitudinally adjustable on said 30 section, a belt pulley having its shaft journaled in said carriage and extending through said slots, cover plates over the slots of said section and connected with the shaft of the pulley, a doffer having its upper end contiguous to the pulley, a support for the doffer secured to the cover plates and movable therewith, and a slide connected with the doffer and extending beneath the upper reach of the 35 belt. 40

45 5. In a belt distributor, a housing having pulleys at each end thereof, a belt traveling in said housing and supported on said pulleys, a supporting plate over which said belt travels, a doffer contiguous to one of the pulleys and having a slide extending between the belt and the plate, and a discharge outlet 50 extending from the plate for discharging cotton outside of the housing.

6. In a belt distributor, a housing having 55 an idler section intermediate its ends provided with side slots, a carriage movably mounted on the housing section, pulleys within the section, shafts on which the pulleys are mounted extending through the section slots and journaled in the carriage, means for driving one pulley from the other, and cover plates over the section slots between the pulley shafts. 60

7. In a belt distributor, an elongated housing comprising end sections and intermedi- 65

ate sections, a drag board connecting said sections, pulleys journaled in the end sections, a distributor belt between the pulleys traversing said board, a driving connection for one of the pulleys, a take-up for the other pulley, and means for doffing the cotton from one of the pulleys and delivering it intermediate the belt and board whereby the doffed cotton is conducted by the belt to a point of discharge. 70 75

8. The combination as defined by claim 7, with means for jointly adjusting said doffer and take-up pulley relative to an end of the drag board.

9. The combination as defined by claim 7, 80 and a choke valve on the end section adjacent the driven pulley and overlying the upper reach of the distributor belt and movable away from the belt.

10. In a belt distributor, a housing including end sections, pulleys journaled in said sections, a distributor belt extending between the pulleys, a take-up for one of said pulleys, a drag board connecting the sections and extending beneath the upper reach of the belt 90 intermediate the pulleys, and a doffer adjustable with the take-up pulley toward and from one end of the board.

In testimony whereof we affix our signatures. 95
